CAR CONSTRUCTION

John P. Anderson, Koppel, Pa., assignor, by mesne assignments, to Koppel Industrial Car and Equipment Company, McKees Rocks, Pa., a corporation of Pennsylvania

Application January 31, 1931, Serial No. 512,623

14 Claims. (Cl. 105—276)

My invention relates to railway cars and in particular to that type of car known as a dump car having doors forming the side walls of the body and opening outwardly and downwardly as 5 the body is tilted and has for its object the provision of means for assisting the door controlling mechanism in holding the doors locked in closed position when the car is in transit.

Another object of my invention is to provide a 10 means for holding the door on the rising side of the body closed while the respective door controlling mechanism is out of engagement with the underframe of the car.

A further object of my invention is to provide 15 a means of maintaining the car body in position on the car underframe during abnormal service conditions.

Referring now to the drawings, Fig. 1 is a side elevation of a portion of a dump car embodying 20 my invention; Fig. 2 is a transverse section along the lines 2—2 of Fig. 1 showing in full lines the door controlling and locking mechanism with the associated parts of the car body shown in dot-and-dash lines; Fig. 3 is a section taken along 25 the lines 3—3 of Fig. 2 having the locking mechanism shown in full lines with the balance of the door controlling mechanism and car body in dot-and-dash lines; Fig. 4 is a transverse section through the car body showing the body in fully 30 tilted position and the door locking mechanism maintaining the rising door locked in closed position; Fig. 5 is a plan view of a portion of the underframe along the lines 5—5 of Fig. 4 showing the means for mounting the locking bars on 35 the underframe; Fig. 6 is a transverse section through the car showing the preferred method of mounting the body on the underframe and the provision of means for pivoting the body on the underframe during the tilting of the car body; 40 Fig. 7 is a half-section similar to Fig. 6 and shows a modification of the method of mounting the body on the underframe.

Referring now in detail to the drawings where like reference characters refer to like parts, reference character 1 indicates a dump car having an underframe 2, the usual trucks 3, and a body 4 mounted on the underframe 2 and adapted to tilt about either side thereof. No specific means has been provided for tilting the body but it is 45 to be understood that any of the mechanical means known to the prior art and suitable to this type of dump car may be employed, it being understood that cars of the type on which the use of my invention is contemplated are usually 50 too unwieldy to be tilted by hand. Extending

along each side of the body and preferably forming the major portion of the side wall thereof are doors 5 which are preferably hinged adjacent the floor of the body and open outwardly and downwardly as the body is tilted.

In the embodiment of my invention as disclosed in the drawings, the door controlling mechanism is mounted adjacent each end of the car body and provides independent mechanisms for each car door. The door mechanism shown in the drawings is a continuation in part of the door mechanism described and claimed by me in an application filed September 6, 1929, Serial No. 390,731 and it will suffice here to say that these door mechanisms 9 are pivotally mounted on the body, 10 having one end attached to its respective door and the other end in engagement with the underframe to control the movements of the active door by the tilting of the body.

From an inspection of Fig. 4 of the drawings it 20 will be apparent that door mechanisms of this character will control the opening door on the descending side of the body but have no control of the door on the rising side which necessitates the provision of a means for maintaining the door 25 on the rising side of the body closed during the tilting and righting movements of the body, or in other words, while the door controlling mechanism secured to the inactive door is out of engagement with the car underframe. Such a 30 means is provided by the levers 6 which are pivotally mounted at each side of the car body adjacent the door mechanism and extend across the underframe where the opposite end of the lever 6 is pivotally mounted adjacent the side of 35 the underframe.

By referring to Fig. 3 of the drawings it will be noted that the door controlling mechanisms are mounted in a line transversely of the car and the locking levers 6 are disposed on opposite sides of 40 the door controlling mechanisms with the ends of the levers alternately pivotally connecting to the underframe and car body by means of the pins 7 and 8. Projecting outwardly from each of the members 9 of the door controlling mechanism 45 are stops 10 which are adapted to be engaged by the levers 6 whose function will be further described as the description proceeds.

By referring to Figs. 3 and 5 of the drawings it will be noted that under normal service conditions the body in turning about its respective pivots will automatically retain the members 9 in position to bear on the track 12 secured to the underframe. However, any tendency of the body to move longitudinally of the underframe would 50 55

cause the rollers secured to the door members 9 to leave this track and such movement might result in injury to the door mechanism or other parts of the car body. The levers 6, by reason 5 of their position transversely of the underframe, being secured within the U-shaped members 13 and to the opposite side of the car body, will act as stops to prevent such longitudinal movement of the body. In addition to this function the 10 levers 6 will also act as guides to the members 9 and should the body momentarily leave the underframe the levers 6 would guide the body in the return to its respective trunnions.

The particular method of mounting the car 15 body on the underframe has no bearing on my invention since the invention can be adapted to a car which is mounted directly on the underframe and adapted to roll upon the underframe for the initial dumping movement and complete 20 the dumping movement about a pivot mounted at the side of the body as disclosed in Fig. 6 of the drawings and described in my co-pending application filed January 31, 1931, Serial No. 512,624, or the body may be supported on spaced pivots 25 located on opposite sides of the underframe as shown in Fig. 7, of the drawings; it only being necessary to modify the shape of the levers 6 to accommodate the differences in initial dumping movement of the car body.

30 Referring now to Figs. 2, 3 and 4 of the drawings, assume the body to be in the position as shown in Fig. 2 and it is desired to tilt the body about the right side of the underframe into the position shown in Fig. 4 of the drawings. In 35 Fig. 2 the body being horizontal the levers 6, attached on opposite sides of the underframe and extending transversely of the underframe to engagement with the opposite side of the car body, are supported on the underframe and the door 40 controlling mechanism of each door, by reason of its engagement with the underframe, maintains its respective door locked in closed position. As the body begins to tilt, the door controlling mechanism secured to the door on the left side of the 45 body moves out of engagement with the underframe as the body rises. The lever 6 secured to the left side of the body moves upwardly with the body and into engagement with the stop 10 on the adjacent member 9 of the door controlling 50 mechanism. Due to its connection to the body and underframe this lever 6 is held in engagement with the stop 10 of the adjacent member 9 throughout the tilting and righting movements 55 of the body and prevents downward movement of the free end of the member 9, thus holding the attached door closed.

The member 9 of the door controlling mechanism secured to the door on the right side of the body by reason of its connection to the car 60 body and the downward movement of the opening door, moves transversely of the underframe towards the descending door to control the opening of the door with the tilting of the body. In this manner the door member 9 moves away from 65 the lever 6 which is pivoted to the right side of the body and which remains inactive during the righting and tilting movements of the car body. By referring to Fig. 4 of the drawings it will be seen that the levers 6 at their points of mounting 70 to the underframe are slotted as at 11 which permit transverse movement of the levers relative to the underframe, to compensate for any outward movement by reason of their connection to the body, during the tilting and righting movements 75 of the car body.

During the return of the body to a horizontal position the lever 6 secured to the left side of the body moves downward with the body until it engages with the underframe. The free end of the lever 9 of the door mechanism, upon engagement with the underframe, again resumes control of the car door and holds the door closed until the body is fully returned to a horizontal position. Should the body be tilted about the left side of the underframe and same action as described 10 would take place excepting that the movements of the door mechanisms on opposite sides of the body would be reversed.

Having thus described the invention what I claim as new and desire to secure by Letters 15 Patent is:

1. In a dump car, an underframe, a body tiltably mounted on said underframe, doors for said body hinged adjacent the floor thereof and forming the side walls, a door operating mechanism 20 mounted on the body and controlling the movement of the doors through engagement with said underframe, means mounted on said body and underframe and actuated by the tilting body for selectively limiting movement of the door controlling mechanism.

2. In a dump car, an underframe, a body tiltably mounted on said underframe, doors for said body hinged adjacent the floor thereof, a member rotatably mounted on the body in engagement with the adjacent door and underframe for controlling the movement of the door as the body tilts about the adjacent part of the underframe and a member mounted on the body adjacent said door member and controlled by the 30 tilting body to limit movement of the door controlling member relative to the body when the body is out of engagement with the underframe.

3. In a dump car, an underframe, a body supported directly on said underframe and tiltably about either side thereof, doors for said body hinged adjacent the floor thereof, a door mechanism mounted on the body adjacent each side door for controlling movement of its respective 40 door as the body moves in dumping and a member mounted on the underframe and extending across the underframe to an engagement with the body adjacent each door mechanism, said member limiting movement of the door controlling mechanism when the body is out of engagement with the underframe.

4. In a dump car, in combination, a tiltably mounted body, doors hinged adjacent the floor thereof and opening outwardly and downwardly as the body tilts about the adjacent side of the underframe, a member rotatably mounted on the body in engagement with the adjacent door and underframe and a stop mounted on said body and controlled by the tilting movement of the body, for limiting the rotation of said member.

5. In a dump car, an underframe, a body tiltably mounted on said underframe, doors hinged adjacent the floor of said body and opening outwardly and downwardly by gravity as the body tilts about the adjacent side of the underframe, a member mounted on the body adjacent each door, said member having its outer end in engagement with the adjacent door and its inner end in engagement with the adjacent portion of the underframe so as to limit the opening of the door by the tilting movement of the body, a member mounted on said underframe and controlled by the tilting body, said member limiting the downward movement of said rotatable member mounted on the body.

6. In a dump car, an underframe, a body tiltably mounted on said underframe and having a plurality of supports spaced transversely of the underframe for maintaining the body in stable equilibrium, doors hinged adjacent each side of said body, a mechanism mounted on the body adjacent its respective door and controlling the movement thereof through engagement with the underframe, a member mounted on the body adjacent each door mechanism and extending transversely of the underframe, said members controlling the downward movement of said doors when said mechanism is out of engagement with the underframe.
- 15 7. In a dump car, an underframe, a body tiltably mounted thereon, doors for each side of said body hinged adjacent the floor thereof, mechanisms for each side door controlling the movement thereof, levers connected adjacent each side of the body and extending transversely of the underframe to engage therewith adjacent the sides thereof, said levers acting through said mechanisms to control the door on the elevated side of the body during dumping.
- 25 8. In a dump car, an underframe, a body tiltably mounted on said underframe, doors forming the sides of said body and hinged adjacent the floor thereof, independent mechanisms for each door being mounted on the body and controlling the doors through engagement with the underframe, and means mounted on said body and controlled by the tilting thereof to limit movement of the door controlling mechanism when out of engagement with the underframe.
- 35 9. In a dump car, an underframe, a body supported in stable equilibrium on said underframe, trunnions adjacent each side of said underframe about which the body tilts in dumping, doors for said body hinged adjacent the floor thereof, door controlling mechanisms mounted on the body adjacent each door, and supplemental door controlling mechanisms mounted on the body and extending across the underframe to adjacent the said trunnions.
- 45 10. In a dump car, in combination, an underframe, a body tiltably mounted on said underframe, doors for said body hinged adjacent the floor thereof, a door controlling mechanism for each door mounted on said body, a member mounted adjacent each side of said underframe and extending across said underframe to a connection to said body, each of said members being capable of limited transverse movement relative to said underframe.
- 55 11. In a dump car, in combination, an underframe, a tiltably mounted body, doors hinged adjacent the floors of said body and forming the side walls thereof, independent mechanisms at each side of said body for controlling the movements of the doors as the body tilts about the adjacent side of said underframe and a member disposed transversely of said underframe adjacent each door mechanism, one end of each member being pivotally mounted to the underframe and actuated by the tilting body to control the door when the body tilts about the opposite side of said underframe.
12. In a dump car, in combination, an underframe, a body supported thereon and tiltably about a side thereof, a door forming a side wall of the body and hinged adjacent the floor, a control mechanism for the door, comprising a member mounted, intermediate its ends, on the body and having one end connected to the door, the opposite end engaging the underframe for movement transversely thereof, and a member connected to the body adjacent the door controlling mechanism and to the opposite side of the underframe, said latter member limiting the movement of the door mechanism when the mechanism is out of engagement with the underframe.
13. In a dump car, in combination, an underframe, a body tiltably mounted thereon, doors forming the side walls of the body and opening outwardly and downwardly as the body is tilted, a door controlling mechanism adjacent each side of the body, said mechanism comprising an arm pivotally mounted upon the body having its outer end connected to the door and its inner end slidably engaging the underframe, and a member disposed transversely of the underframe, one end of the member being connected to the body and the opposite end connected to the underframe, said member limiting movement of the arm when the latter is free of the underframe.
14. In a dump car, in combination, an underframe, a body mounted to tilt about either side of the underframe, doors hinged adjacent the floor of the body and forming the walls thereof, and a door operating mechanism including a member mounted on the body adjacent each door having opposite ends adapted to engage the door and underframe respectively, and means mounted on the body adjacent each member and extending beneath the latter to an engagement with the underframe, for controlling the adjacent member when the body is tilting about the opposite side of the underframe.

JOHN P. ANDERSON. 55
